RAIL LUBRICATOR

Lewis S. Elmer, Baltimore, Md.

Application November 25, 1930, Serial No. 498,042

13 Claims. (Cl. 184—3)

My invention relates to improvements in railway track rail lubricators and has particular reference to devices for car wheel actuated lubricators for street railways, especially of the grooved type curved rail, but it is applicable to other rails and other locations. It may be applied to closely paralleled T rails where one of the rails is a guard, and the space between the parallel rails is filled with suitable material, so as to leave only a groove between the heads of the rails.

My invention embodies improvements developed from the practical operation on a railway, of a lubricating device based upon the principles of my invention of a rail lubricator for which application for patent was filed in the United States Patent Office on March 14th, 1930, Serial Number 435,861.

One of the objects of my present invention is to provide a durable, adjustable, combined car wheel actuated reciprocating plunger and lubricant discharge nozzle head, operating vertically through a perforation in a groove of a railway rail, and a piston type lubricant pump, preferably located between the guard rail flange and the foot flange of the said rail, the said pump having an intake connection to a lubricant tank or reservoir, which may be located between the parallel rails of the same track, or in any other convenient position, and said reservoir may supply one or a multiplicity of my lubricating devices and said pump having its vertical piston rod held concentric with the rail perforation by the plunger head.

A further object of my invention is to provide means for easily adjusting and retaining the discharge nozzle in any desired direction.

Another object is to provide means for self adjustment of the length of the pump piston stroke to compensate for changing degrees of fluidity of the lubricant, coincident with changes of temperature.

Another object is to provide means of uniformly distributing the lubricant discharged by a car wheel actuated pump, to the groove surfaces of the railway track rail, especially throughout the curved portions thereof.

Another object is to provide an electrically heated compartment enclosing the lubricant pump and supply to prevent congealing of the lubricant during cold weather.

I attain these objects by the mechanism illustrated in the accompanying drawing, in which like numerals refer to like parts, and in which—

Figure 1 is an elevation of part and vertical section of part of the lubricator, and of the rail-

way rail to which it is fitted, and of the enclosing chamber shell, containing an electric heater.

Figure 2 is a sectional plan view, on the line 2—2 of Figure 1, showing the arrangement of the adjustable plunger nozzle head, the position retaining flexible stops, retaining set screw, lateral check valve connections to auxiliary discharge heads when needed, and to the duct leading to the source of lubricant supply.

Figure 3 is a sectional view on line 3—3 of Figure 1.

Figure 4 is a sectional elevation of the plunger-nozzle head, operating through an opening in the groove of a railway rail, and of a lubricant absorbent pad.

Figure 5 is a plan view of a thermal equalizing member.

My improved lubricator comprises the plunger-nozzle dome-shaped head 1, provided with a groove 4, a duct 6 terminating at its upper extremity in the mouth or orifice 5. The duct 6 is usually concentric with the plunger until near the top or dome of same, when it is deflected, usually at an angle so as to emerge at the side of the base of said domed part of said head and in approximately the direction of the passage of an actuating car wheel flange over it. The mouth 5 of the duct 6 opens vertically on its inner side and its outer edge coincides with the adjacent vertical surface of the head member 1. Thus the mouth 5 forms a suitable entrance for a tool to be used to rotate the plunger head 1, even though the dome portion of said head be lowered below the surface of the rail groove 11. The absorbent member 7 may be applied to retain a portion of the lubricant, after each discharge of same from the plunger-nozzle and to later transfer this lubricant to other passing car wheel flanges.

The plunger-nozzle 1 moves reciprocally downward when depressed by a car wheel flange 9 passing over it, and upward when released, with in the opening 1' of the rail flange 33 into the rail groove 11, the resilient member 27 of the pump 3 being the actuating force to produce the upward motion thereof.

The groove 4 of the plunger-nozzle head 1 is engaged by the key 13 to the collar 12, so that the plunger-nozzle head rises and falls vertically in the position where held by the rotatable collar 12.

The collar 12 having the key 13 engaging the groove 4 of the plunger-nozzle head 1 secures said head member from rotation while said collar 12 is secured in a fixed position by the set screw 14 or by the resilient stop 16, thereby directing the mouth 5 of the duct 6 in a predetermined

- radial position, while the member 1 is free to move reciprocally in a vertical direction. 80
- The threaded connection 15, joining the plunger-nozzle head 1 to the hollow piston rod 5 18 having the discharge duct 6, leading from the pump chamber 3 permits the plunger-nozzle member 1 to be adjusted upwardly or downwardly when rotated by a suitable tool inserted through the mouth 5 into the inclined portion of the duct 10 6. Thus an upward adjustment of the head 1 permits a longer downward stroke when the head receives the impulse from a passing car wheel flange, resulting in a greater displacement of the lubricant contained within the pump chamber 15 3, and a greater quantity of lubricant discharged through the duct 6 and the mouth 5, and conversely a rotation of the head 1 on the thread 15 in the opposite direction, correspondingly reduces the quantity of lubricant discharged. 90
- The thermal member 19, located beneath the collar 12, stops the upward movement of the piston 20. 95
- The thermal member 19, comprises a suitable hollow metallic ring with its diameter in a horizontal plane, its interior and exterior vertical surfaces being corrugated to form a series of horizontal circular ridges. The ring 19, comprises a thin metallic shell filled with mercury or other suitable thermo-expandable substance, or the thermal member 19, may comprise any suitable shape or material capable of sufficient vertical expansion and contraction under influence of temperature variations, so as to permit a longer or shorter piston stroke and thereby an increased or decreased volume of lubricant to be pumped at each depression of the operating plunger 1. 100
- Thus as temperature changes affect the fluidity of the lubricant simultaneous changes in length of piston stroke effect compensation of the amount of lubricant discharged through the mouth 5, of the plunger-nozzle 1. The spring 27, returns the piston and plunger to their normal elevated positions, after passage of the operating car wheel. 105
- Attached to the lower side of the piston or plunger 20 is an extension which supports the discharge valve 26 and carries the grooved slide guides 24 which slide over the projecting fixed guides 25 rigidly attached to the body member or shell 21 of the pump, thus preventing the rotation of the piston 20 about its axis and permitting the thread 15 to function in adjusting the rotatable head 1 as described heretofore. 110
- The pump body comprises a top section 22, having a suitable gasket 37 to make a lubricant leak proof joint against the under side of the rail flange member 33, with the plunger-nozzle 1 passing downwardly into the member 22 and thereby retaining the pump in position with relation to the opening 1' of the rail 8. 115
- The central pump member 21 is firmly secured to the top section 22 and to the bottom section 23. 120
- The bottom section 23 is further held in position with the base of the rail 8, by set screws 29 and by the intake duct 31, which leads to a suitable reservoir of lubricant. 125
- The chamber 36 enclosing the lubricator within the upper and base or foot flanges of the rail 8, contains the electric heater 35, of any suitable type, for use during periods of low atmospheric temperature, to maintain the lubricant in a fluid or semi-fluid state. 130
- The intake check valve 30 of the lubricator may have the lateral check valves and outlet ducts connected to any number of lubricators. 135
75. I claim:
1. The combination of a chamber, having a girder track rail forming one side thereof and containing within said chamber, an electric heater in proximity to a pump and to a duct, leading from a reservoir of suitable lubricant, to the intake valve of said pump; a pump directly operable by an approximately vertical tubular plunger, comprising the discharge duct of said pump; said plunger-discharge member having a combined adjustable head and nozzle member protruding upward, through an orifice into the bottom of the groove member of said rail; said head capable of being suitably directed and adjusted to cause the said pump to emit a suitable quantity of lubricant in a suitable direction into said rail groove and upon each car wheel flange, which depresses said plunger head, thereby operating the device. 140
  2. A car wheel operable railway rail lubricator comprising a cylindrical dome-shaped plunger head having an internal passage for conveying lubricant from a pump to a port for said head suitable to discharge lubricant into a rail groove for distribution therein by the operating car wheel flange, said plunger head being in operable adjustable connection through a vertical perforation of a rail groove by a threaded non-rotatable hollow piston rod with the lubricant pump mounted beneath the rail groove perforation, said port being suitable as a socket to receive a tool capable of quickly rotating the plunger head for adjustment of the volume of lubricant discharged from its port when operated by a man standing over the rail, a collar rotatably mounted within a recess of the upper portion of a lubricant pump 145 housing and encircling the plunger head and loosely keyed to a vertical groove therein so as to permit vertical movement of the plunger to operate the connected pump and to prevent rotation of the plunger head within the collar, a resilient stop suitable to check rotation of the collar so as to direct the lubricant discharged from the port into the rail groove, and suitable connection of the pump with a source of lubricant supply. 150
  3. A device as claimed in claim 2, having a vertical expandable thermostatic member with a central opening suitable to permit the movement of the pump piston rod and connected plunger head, said thermostatic member suitably mounted to serve as a stop for the pump piston when rising so that expansion of the thermostat downward will check the piston to reduce the volume of lubricant pumped and contraction of the thermostat will increase the volume of lubricant 155 at each impulse. 160
  4. A device as claimed in claim 2, having thermostatic means of varying the volume of lubricant discharged into the rail groove as temperature varies the viscosity of the lubricant. 165
  5. In a railway rail lubricator comprising a vertical piston type pump secured operably beneath a perforation of a rail groove and having a non-rotatable hollow threaded piston rod and combined discharge duct, a rotatable plunger head 170 loosely threaded thereto, operable within a rail groove perforation by a car wheel flange, a duct within the plunger head connecting the discharge duct of the pump with a port at the side of the dome-shaped head of the plunger, a port in the plunger head suitable to discharge lubricant into a rail groove, and adapted to receive a tool for rotatably adjusting the plunger head from above the rail surface, means of securing the plunger head from accidental rotation by the em- 175

- ployment of a vertical groove in the plunger head with a loosely fitted key therein, the key being rigidly attached to a collar surrounding the plunger head, the collar being rotatably mounted 5 within a recess of the pump housing and checked from rotation at a predetermined point by a resilient stop, means of supplying lubricant to the pump, and resilient means of restoring that piston and plunger head to their normal elevated 10 positions. 6. A car wheel operable railway rail lubricator comprising a cylindrical dome-shaped plunger head having an internal passage for lubricant discharged from a pump, a port for the lubricant 15 passage at the side of the dome of the head suitable to discharge lubricant into a rail groove and adapted to receive a portion of a tool to manually rotate the head from above the rail as means of adjustment of the lubricant pump, 20 said plunger head having an internally threaded passage being in operable threaded and adjustable connection through a vertical perforation of a rail groove with a non-rotatable combined piston rod and discharge duct of the lubricant 25 pump, means of adjusting the pump by a collar encircling the plunger head and loosely keyed to a vertical groove therein to permit vertical movement and to prevent rotation of the plunger head, said collar being rotatable within a circular recess of a lubricant pump housing, a resilient stop 30 suitable to check rotation of the collar at a predetermined point so that the port will discharge lubricant into the rail groove and prevent accidental rotation of the plunger head, and suitable 35 means of securing the pump in operable position beneath the perforation of the rail groove, means of supplying the pump with lubricant, and means of restoring the plunger head to its normal position. 40 7. A device as claimed in claim 6, having a thermostatic vertically expandible member lying immediately under the collar which surrounds the plunger head said thermostat being suitable to vary the volume of lubricant discharged from 45 the pump by checking the pump piston at varying points as the thermostat expands or contracts and thereby to compensate for changing viscosity of the lubricant caused by changing temperatures. 8. A device as claimed in claim 5 having a 50 thermostat operable between the pump piston and the collar surrounding the plunger head, and having a central opening suitable to permit movement therein of the pump plunger head and piston rod, and being adapted to check the pump piston at various points, to thereby vary the volume of lubricant pumped and to compensate for the changing viscosity of the lubricant, caused by changing temperatures. 55 9. A car wheel actuated rail lubricating device comprising a vertical cylindrical plunger head having a dome shaped top protectively located below a rail tread and projecting through a perforation of a rail groove in position to be 60 operated by a flange of a passing car wheel, said head having a port suitable to discharge lubricant into the rail groove and adapted to receive a tool for rotatably adjusting the plunger head from above the rail, means of securing the plunger head from accidental rotation by the employment 65 of a vertical groove in the plunger head with a loosely fitted key therein, the key being attached to a collar surrounding the plunger head, the collar being rotatably mounted within a recess of a pump housing and checked from rotation at a predetermined point by a resilient stop, 70 said plunger head having an internal lubricant passage from its port to the discharge duct of the pump, means of adjusting the stroke of the pump by the plunger head being loosely and rotatably threaded to a non-rotatable hollow piston rod and combined discharge duct of the pump, 75 said pump being secured beneath the rail perforation with the plunger head assisting in retaining it in position, resilient means within the pump of restoring the plunger head to its normal position after each operation, and means of supplying lubricant to the pump. 80 10. A device as claimed in claim 9 having a thermostat operable between the piston of the pump and the collar surrounding the plunger head, said thermostat having an opening suitable to permit movement therein of the pump plunger head and piston rod, and being adapted to stop the rising of the pump piston at various 85 points as changing temperatures cause expansion or contraction of the said thermostat, thereby effecting compensation of the volume of lubricant pumped by increasing or decreasing the length of the stroke of the piston as changing temperatures vary the viscosity of the lubricant. 90 11. A car wheel actuated rail lubricating device comprising a vertical plunger head having a dome shaped top and an internal passage for lubricant discharged from a pump and having a port for the lubricant passage at the side of the dome of the head, suitable to discharge lubricant into a rail groove and adapted to receive a tool to manually rotate the head from above the rail as a means of adjusting the stroke of the lubricant pump and thereby regulating the volume 95 of lubricant discharged into the rail groove for distribution therein by passing car wheel flanges, the plunger head being in operable threaded and adjustable connection through a vertical perforation of a rail groove with a non-rotatable combined piston rod and discharge duct of the lubricant pump, a collar encircling the plunger head and loosely keyed to a longitudinal groove 100 therein to permit reciprocating movement and to prevent rotation of the plunger head, said collar being rotatable within a recess of the lubricating pump housing, a resilient stop suitable to check rotation of the collar at a definite point to permit the port of the plunger head to discharge lubricant into the rail groove and to 105 prevent accidental rotation of the plunger head, the plunger head being in position to be depressed by the flange of each passing car wheel but protectively located below the rail tread to avoid interference of vehicular traffic, suitable 110 means of securing the pump in operable position beneath the perforation of the rail groove and aligned therewith by the plunger head, means of supplying the pump with lubricant, and means of restoring the plunger head after each operation to its normal elevated position. 115 12. A railway rail lubricator comprising a cylindrical dome shaped plunger head being in position to be actuated by a passing car wheel flange and having an internal passage for lubricant and a port for the same at the side of its dome and protectively located below the crown thereof being suitable to discharge lubricant into a rail groove and adapted to receive a tool to manually 120 rotate the plunger head from above the rail as a means of adjusting the stroke of a connected lubricant pump, said plunger head being in operable threaded and adjustable connection through a perforation of the rail groove with a non-rotatable combined piston rod and discharge 125 duct of the pump. 130 13. A device as claimed in claim 12 having a 135 thermostat operable between the piston of the pump and the collar surrounding the plunger head, said thermostat having an opening suitable to permit movement therein of the pump plunger head and piston rod, and being adapted to stop the rising of the pump piston at various points as changing temperatures cause expansion or contraction of the said thermostat, thereby effecting compensation of the volume of lubricant pumped by increasing or decreasing the length of the stroke of the piston as changing temperatures vary the viscosity of the lubricant. 140 14. A device as claimed in claim 13 having a 145 thermostat operable between the piston of the pump and the collar surrounding the plunger head, said thermostat having an opening suitable to permit movement therein of the pump plunger head and piston rod, and being adapted to stop the rising of the pump piston at various points as changing temperatures cause expansion or contraction of the said thermostat, thereby effecting compensation of the volume of lubricant pumped by increasing or decreasing the length of the stroke of the piston as changing temperatures vary the viscosity of the lubricant. 150

duct of the said pump, a collar around the plunger head and loosely keyed to a longitudinal groove therein to permit reciprocal motion and to prevent rotation of the head, the collar being rotatable within a recess of the lubricant pump housing, a resilient stop suitable to check rotation of the collar at a fixed point so as to secure the port in a desired position and to prevent accidental rotation of the plunger head, means of compensation for the varying volume of lubricant discharged as temperature changes affect the viscosity thereof by the employment of a thermostat interposed between the plunger head collar and the pump piston, means of securing a suitable pump beneath a rail perforation, in operable position with the plunger head, and means of supplying the pump with lubricant.

13. A car wheel flange actuated rail lubricator comprising a dome shaped plunger head operable through a grooved rail perforation and having a threaded internal lubricant duct adjustably and rotatably connected with an externally threaded non-rotatable hollow combined pump piston rod

and discharge duct of a lubricant pump, said pump being secured in operable position beneath a rail groove perforation, a port for the plunger head duct at the side of the dome of the head suitable to discharge lubricant into the groove of the rail when the head is depressed by a passing car wheel flange, said port being adapted to receive a tool for rotatably adjusting the head and thereby adjusting the stroke of the pump from above the rail, means of securing the plunger head from accidental rotation by the employment of a vertical groove in the plunger head with a loosely fitted key therein, the key being rigidly attached to a collar surrounding the plunger head and the collar being rotatably mounted within a recess of the pump housing and checked from accidental rotation at a predetermined point by a resilient stop, means of supplying lubricant to the pump, and means of restoring the plunger head to its normal position.
